UNITED STATES PATENT OFFICE.

GUS MAJOR KAISER AND ALFRED SAMUEL HECHT, OF NEW YORK, N. Y.

TOY AEROPLANE.

1,035,017.

Specification of Letters Patent.

Patented Aug. 6, 1912.

Application filed July 6, 1911. Serial No. 637,073.

To all whom it may concern:

Be it known that we, GUS M. KAISER and ALFRED S. HECHT, both citizens of the United States, and residents of the city of New York, borough of Manhattan, in the county and State of New York, have invented a new and Improved Toy Aeroplane, of which the following is a full, clear, and exact description.

10 Our invention relates to toy aeroplanes, and it has for its object to provide one which may be constructed at trifling expense, so that the aeroplanes may be manufactured in quantities and may be given away for advertising purposes or be sold for a few cents.

We prefer to construct the principal parts of the aeroplane of cardboard, the propeller and the body being each constructed of a 20 single piece of cardboard, the cardboard being scored and folded to the desired shape, after which the parts are pasted together.

Other objects of the invention will appear in the following specification, in which the 25 preferred form of our invention is described.

Similar reference characters refer to similar parts in the several views of the drawings, in which—

30 Figure 1 is a perspective view of the aeroplane; Fig. 2 is a plan view of Fig. 1; Fig. 3 is a plan view showing the blank from which the body of the aeroplane is constructed; Fig. 4 is a plan view of the blank 35 from which the propeller is constructed; Fig. 5 is a rear end view of the blank shown in Fig. 3, partially folded; Fig. 6 is a front end view of the blank shown in Fig. 3, partially folded, and Fig. 7 is a side elevation 40 of the front of the aeroplane.

By referring to the drawings it will be seen that a blank 10 is provided, the sides 11 and 12 of which converge to the right. This blank 10 is scored longitudinally at 45 13, 14 and 15, to form a reinforcing member 16, a bottom member 17 and sides 18 and 19. At the rear end 20 of the reinforcing member 16 there are two flaps 21 which are spaced from each other and which are 50 curved at their inner sides 22. The inner reinforcing member 16 does not extend as far rearwardly as the body of the blank 10. At the rear of the sides 18 and 19 there are flaps 23 and 24, and at the rear of the bottom member 17 there is a flap 25, the flap

25 extending beyond the rear of the flaps 23 and 24 and being scored at 26, so that it may be folded on itself, as indicated in Fig. 5 of the drawings. The inner reinforcing member 16 does not extend as far forward 63 as the side members 18 and 19 and the bottom member 17, the sides 18 and 19 being curved outwardly at 27 and 28, as indicated in Fig. 3 of the drawings. There is also a flap 29, which is a part of the blank 10 and 65 which projects in front of the side member 18. Near the rear of the blank 10 and extending from the side member 19, there is a lateral projection 30, from which is formed the keel member 31. The lateral projecting 70 member 30 is scored at 32 and again at 33, and flaps 34 are formed by cuts 35.

The blank 10, after it has been stamped out and has been scored as indicated, is folded as follows: The side members 18 and 75 19 are bent upwardly relatively to the bottom member 17, the inner reinforcing member 16 is bent within the side members 18 and 19 and the flaps 21 are folded face to face and glued together. The inner reinforcing member 16 is also glued to the bottom member 17 and the inner faces of the side members 18 and 19. The flap 29 is then bent around the front and against the inside of the side member 19 and glued to inclose 85 the body of the aeroplane at the bow. The flaps 23 and 24 are folded on score 36, one in front of the other and are glued together, and the flap 25 is folded at the score 26 and then is folded at the score 36, so that 90 four surfaces of the cardboard will lie face to face at the rear of the body of the aeroplane. The lateral projecting member 30 is bent at the score 37, as shown in Fig. 5 of the drawings, and then it is bent again at 95 the score 32, so that that part between scores 30 and 32 will be against the side member 19 and the remainder of the lateral projecting member 30 between scores 32 and 33 will be disposed against the underside of bottom 103 member 17. The keel member 31 is then bent at the score 33, so that it will be disposed downward, and the flaps 34 are also bent at the score 33, so that they will lie against the bottom of the body of the aeroplane opposite that portion of the lateral projecting member 30 which is disposed between the score 32 and 33. When the lateral projecting member 30 and the flaps 34 are glued to the side member 19 and to the 110

2
bottom of the bottom member 17 of the aeroplane, it will be found that the keel member 31 will be held firmly in position.

5 The propeller 38 is stamped out of the blank 39, and the projecting portions 40 of the blank are bent over the hub portion 41, one at each side between the portions 42, which form the blades. The projecting portions 40 are provided to reinforce the portions 10 at the hub. After the projecting portions 40 have been bent over and have been glued to the central portion of the propeller, the propeller is shaped in a die, so that the propeller blades will be carried, as required.

15 A wire 43 is wound around the propeller 38, and the free terminal 44 of this wire is inserted in orifices 45 in the rear of the body of the aeroplane and also through orifices which are made in the flaps 21. An 20 elastic 46 is then secured to the free terminal 44 of the wire, forward of the flaps 21, and this elastic is secured at the forward end of the body of the aeroplane to a hook 47, which in turn is secured to the bottom member 17. A bead 48 is mounted on the wire 25 43 at the rear of the body of the aeroplane, to reduce friction, a twist being made in the wire 43 in the rear of the head 48, to limit the forward movement of the propeller 38.

30 Two plane members 50 and 51 are provided, the plane member 51 being preferably smaller than the plane member 50. The plane member 50 is mounted on the body member 52 of the aeroplane and is disposed 35 near the rear of the body and above the keel member 31. An elastic band 53 is then disposed under and across the body member 52, over and across the plane member 50, and again under the body and at the rear of the 40 keel member 31, to hold the plane 50 yieldingly in position. The other plane 50 is mounted on the body 52 at the bow 54, the curves 27 and 28 in the sides 18 and 19 causing the body member 52 at the bow to 45 curve upward and forward, so that when the plane 51 is moved forwardly, its forward edge will be raised slightly relatively to its rear edge. By moving the plane 51 forward or rearward at the bow of the body 50 52, the direction as to elevation in which the aeroplane will be driven will be regulated. The plane 51 is secured in the same manner as the plane 53 by a rubber band 55.

Having thus described our invention, we 55 claim as new and desire to secure by Letters Patent:

1. In an aeroplane, a piece of cardboard scored to form a bottom, sides and an inner

reinforcing member of a body, the sides of the cardboard being bent at an angle to the bottom of the reinforcing member, said reinforcing member being secured between the sides.

2. In an aeroplane, a piece of cardboard 65 scored to form a bottom, sides and a reinforcing member having two flaps at one end, the sides of the cardboard being bent relatively to the bottom and the reinforcing member being secured between the sides with the flaps secured face to face.

3. In an aeroplane, a piece of cardboard 70 scored to form a bottom, sides and an inner reinforcing member of a body, the piece of cardboard having flaps at one end, the sides of the cardboard being bent relatively to the 75 bottom, the reinforcing member being secured between the sides and the flaps being secured face to face.

4. In an aeroplane, a piece of cardboard, the sides of which converge in one direction, 80 the cardboard being scored to form a bottom, sides and an inner reinforcing member of a tapering body, the sides of the cardboard being bent relatively to the bottom and the reinforcing member being secured 85 between the sides.

5. In an aeroplane, a piece of cardboard 90 scored to form a bottom and sides of a body having a lateral extension for forming a keel, the sides being bent relatively to the bottom and the lateral extensions being bent under the bottom, and means for securing the parts in place.

6. In an aeroplane, a piece of cardboard 95 scored to form a bottom, sides and an inner reinforcing member having a flap with an orifice, there being a second flap with an orifice at one end of the piece of cardboard, the cardboard being bent, with the second flap secured across the end of the device and 100 the reinforcing member secured between the sides, with the first-mentioned flap spaced from the second-mentioned flap and secured across from one side to the other, a stud disposed in the orifices and projecting from the 105 device, a propeller secured to the stud beyond the device, and means for rotating the stud.

In testimony whereof we have signed our names to this specification in the presence of 110 two subscribing witnesses.

GUS MAJOR KAISER.
ALFRED SAMUEL HECHT.
